MAGNETO

Leonard Griffiths and Sidney H. Franklin, Coventry, England, assignors to General Electric Company, a corporation of New York

Application January 30, 1936, Serial No. 61,614
In Great Britain February 26, 1935

7 Claims. (Cl. 171—209)

Our invention relates to ignition systems for internal combustion engines and more particularly to coupling connections between the magneto and distributor in combustion engine ignition systems.

It is an object of our invention to provide an improved manually operable arrangement for selectively controlling the timing of the opening and closing of the distributor contacts with respect to the operation of the magneto.

Further objects and advantages of our invention will become apparent as the following description proceeds, and the features of novelty which characterize our invention will be pointed out with particularity in the claims annexed to and forming a part of this specification.

For a better understanding of our invention, reference may be had to the accompanying drawing in which Fig. 1 is an end elevation of a magneto provided with a coupling arrangement embodying our invention; Fig. 2 is a side elevation, partly in section, of the magneto and coupling arrangement therefor shown in Fig. 1; Fig. 3 is a sectional view along the line 3—3 of the coupling connection shown in Fig. 2, and Fig. 4 is a detailed view in section along the line 4—4 of a gear and spindle included in the coupling connection shown in Fig. 3.

Referring to the drawing, we have shown in Fig. 1 a magneto 10 provided with a frame 11 having an integral annular housing 12 formed on one end thereof which is adapted to contain a distributor of the ordinary type for a multi-cylinder internal combustion engine. The distributor contained in the housing 12 includes a cam of the conventional type which opens and closes the contacts of the distributor, the cam being driven by an upwardly extending rotatable spindle 13. The spindle 13 is connected in driving relation with a rotatable shaft 14 of the magneto 10 by a coupling arrangement embodying our invention. This coupling includes a manually operable arrangement, hereinafter described, for selectively varying the angular relation between the spindle 13 and the shaft 14 about their respective axes. This selective manual variation of the angular relation between the spindle 13 and the shaft 14 effects an adjustment of the ignition timing since the shaft 14 is rotated by a mechanism connected to the internal combustion engine, with which the magneto and distributor is used, in such manner that the position of the shaft 14 bears a positive relationship to some definite position of the engine pistons. As a consequence, a variation in

the angular relation between the spindle 13 and the shaft 14 will cause the cam, attached to the upper end of the spindle 13, to open and close the distributor contacts earlier or later for a specified position of the shaft 14 and thus of the engine pistons.

The shaft 14 of the magneto 10 supports a rotatable magneto rotor 15 within the housing 11 and one end of the shaft 14 extends through an aperture 16 formed in the end of the magneto 10 housing. The shaft 14 is journaled in suitable anti-friction bearings supported in the magneto housing 11. As shown in Fig. 2, one of these anti-friction bearings includes a series of balls 17, which are rotatably supported between annular inner and outer races 18 and 19, respectively. The inner race 18 is press-fitted on the shaft 14 and the outer race 19 is supported in an annular recess 20 surrounding the inner end of the aperture 16 in the magneto frame 11. A disk-shaped guard 21 is clamped between a shoulder 22, formed on the shaft 14, and the inner sides of the bearing races 18 and 19. The guard 21 extends entirely across the inner side of the space between the bearing races 18 and 19 and prevents the leakage of lubricant therefrom into the magneto frame 11. The guard 21 also prevents the entrance of dirt or other foreign matter into the bearing from the interior of the magneto frame 11. A guard is also provided on the outer side of the bearing in order to prevent the leakage of lubricant from the bearing and the entrance of dirt or other foreign matter therein. This outer guard includes an annular ring 23 which is clamped between the outer bearing race 19 and the bottom of the recess 20 in which the outer bearing race is mounted. The guard ring 23 is provided with an axially extending integral flange 24 having an inwardly extending peripheral portion 25 formed thereon. A series of annular washers 26 made of felt or the like are mounted between the ring 23 and portion 25 of the flange 24, the washers 26 being held in spaced relation by a series of annular metal spacing washers 27. The inner edges of the washers 26 are pressed into wiping contact with the adjacent portion of the shaft 14 and prevent the leakage of lubricant along the shaft.

An integral housing 28 projects from the end 50 of the magneto frame 11 and is provided with a cylindrical bore 29 therein, which surrounds the projecting end portion of the shaft 14. The spindle 13 is journaled in a cylindrical sleeve bearing 30 which is mounted in an aperture 31 55

formed in the upper side of the housing 28. The spindle 13 and shaft 14 are connected together in driving relation by a pair of meshing gears arranged within the housing 28 and secured to the spindle 13 and shaft 14, respectively, one of the gears being movable with respect to its associated member to selectively vary the angular relation between the spindle 13 and shaft 14 about their respective axes. As shown in Figs. 2 and 3, the outwardly extending portion of the shaft 14 is provided with a plurality of splines 32 slidably engaging similar splines 33a formed within a helical gear 33 mounted on the shaft 14. A similar helical gear 34 is arranged at substantially right angles with respect to the gear 33 and meshes therewith. The second helical gear 34 is rigidly secured to the lower portion of the spindle 13, the gear 34 being provided with an axially extending D-shaped hole in which the lower end of the spindle 13 having a flattened side 35 is fitted, as best shown in Fig. 4. Axial displacement of the gear 34 along the spindle 13 is prevented by a washer 36 and nut 37, the nut 37 being threaded on the lower end of the spindle 13.

The helical gear 33 is provided with an axially extending reduced portion 38 at the outer end thereof on which an annular race 39 of an anti-friction type thrust bearing is press-fitted. The thrust bearing also includes an annular race 40 and a plurality of balls 41 which are rotatably mounted between the races 39 and 40, respectively. The race 40 of the thrust bearing is pressed in an annular recess 42 formed in an axially movable disk 43. The outward movement of the disk 43 is limited by a shoulder 44 formed on the inner side of a removable housing cap 45 which extends across the open end of the recess 29 formed in the housing 28. The housing cap 45 is secured in position by a series of screws 46. A pin 47 mounted in a hole 48 formed in the housing cap 45 is provided with an enlarged inner end 49 which is slidably fitted in a registering hole 50 formed in the disk 43 and thus prevents rotative movement of the disk 43, while at the same time permitting axial movement thereof.

The helical gear 33 is biased against an inward axial movement toward the magneto 10 by an arrangement including a helical compression spring 51, the inner end of which is mounted in a centrally located bore 52 formed in the outer end of the shaft 14. The outer end of the spring 51 bears against a cup-shaped closure member 53 which is mounted in the outer end of the extension 38 formed on the helical gear 33. The outer edges 54 of the extension 38 are spun over the adjacent end portion of the closure member 53 in order to hold the same in position. It will thus be seen that the compression spring 51 exerts an outward biasing force on the closure member 53 and, consequently, on the helical gear 33 which tends to move the gear 33 and its thrust bearing, as well as the disk 43, outwardly in an axial direction. This outward axial movement is limited by the shoulder 44 formed on the inner side of the housing cap 45, as was noted above.

We have provided a readily accessible manually operable arrangement for selectively moving the helical gear 33 in an axial direction against the bias of the spring 51 and, consequently, for varying the angular relation between the spindle 13 and shaft 14 about their respective axes so as to adjust the timing of the magneto. This

arrangement includes a sheet metal cup-shaped member 55 surrounding a projection 56 formed on the outer side of the housing cover 45 and rigidly secured to a hollow bushing 57 by a screw 58, which is threaded in a tapped hole 59 formed in the bushing 57. The bushing 57 is rotatably mounted in a bore 45a formed in the housing cover 45. A laterally extending manual operating handle or member 60 is clamped to the cup-shaped member 55 by an annular clamping ring 61 which surrounds the side walls of the cup-shaped member 55 and is held in tight engagement therewith by a screw 62, which passes through the handle 60 and is threaded in suitable holes formed in the adjacent ends 63 of the clamping ring 61.

When the operating handle 60 is rotated by the operator, the member 55, to which the handle 60 is secured, is also rotated as is the bushing 57. This rotative movement of the bushing 57 causes the inner end thereof, which is provided with a V-shaped cam surface 64, to rotate. The disk 43 is provided with an integral centrally located extension 65 slidably mounted in the bore 45a formed in the housing cover 45 and having a complementary V-shaped cam surface 66, which engages the cam surface 64 of the bushing 57. Referring particularly to Fig. 2, it will be seen that when the operating handle 60 and bushing 57 are rotated in a clockwise direction, as viewed from the outer end of the housing 28, that the cam surface 64 will ride up toward the point of the cam surface 66, thus forcing the disk 43 inwardly. This inward movement of the disk 43 also causes the helical gear 33 to be moved axially inward along the splined portion of the shaft 14. Conversely, when the operating handle 60 and bushing 57 are rotated in a counter-clockwise direction, the point of the cam surface 66 will move toward the notch in the cam surface 64 and the compression spring 51 will cause the disk 43 and helical gear 33 to move axially outward. When the helical gear 33 is displaced either inwardly or outwardly along the straight splined portion of the shaft 14, the helical gear 34 which is in mesh with the helical gear 33 will be correspondingly rotated as will the spindle 13, which is secured to the helical gear 34. This rotation of the spindle 13 will in turn effect an adjustment of the ignition timing for, as was pointed out above, the displacement of the spindle 13 will cause the cam attached to its upper end to open and close the distributor contacts earlier or later for a specified position of the shaft 14, which bears a positive relationship to some definite position of the engine pistons.

Additional support for the cam-surfaced extension 65 on the disk 43 and bushing 57 is provided by a dowel pin 67 which is preferably press-fitted within a central bore 68 formed in the bushing 57 and slidably fitted in a centrally located bore 69 formed in the extension 65 of the disk 43.

We have also provided an arrangement for limiting the rotative movement of the cup-shaped member 55 and bushing 57 as well as an arrangement for preventing the axial movement of these parts. A pin 70 which is mounted in a hole 71 formed in the outer end of the housing cover 45 is provided with an enlarged outer end 72 which extends through an arcuate slot 73 formed in the cup-shaped member 55. The engagement of the pin 72 with the opposite ends 75

of the slots 73 thus limits the rotative movement of the member 55 and the bushing 57, which is secured thereto. The length of the slot 73 is designed with relation to the dimensions of the 5 other parts so that when the member 55 is rotated to one extreme position, allowed by the pin 72 and slot 73, the gear 33 will be moved to one extremity of the splines 32 on the shaft 14; and in the other extremity of movement of the member 55, permitted by the pin 72 and slot 73, the gear 33 will be moved to the other extremity of the splines 32 on the shaft 14. Also the gears 33 and 34 are so designed with respect to their co-operating parts that the fully advanced timing 10 position corresponds to the position of the gear 33 to the extreme right, as viewed in Fig. 2, for example, and the fully retarded timing position corresponds to the position of the gear 33 at the extreme left end of its travel. A collar 74, 15 which surrounds the bushing 57 engaging a shoulder 75 formed thereon and is threaded in a tapped recess 76 in the outer end of the housing cap 45, prevents axial displacement of the bushing 57 and disk 55. The initial timing of 20 the magneto, that is, the relative position of the rotor 15 and co-operating field poles when the contacts of the distributor separate may be adjusted by screwing the collar 74 into or out of the recess 76. This initial adjustment can most 25 conveniently be made by first removing the member 55 and then moving the collar 74 to the desired position.

The bore 29 in the housing 28 is normally filled with oil or other lubricant up to the level of the 30 shaft 14. An adequate supply of lubricant is thus had for the helical gears 33 and 34 as well as the thrust bearing 41, the lower portions of 35 which are immersed in the oil. The oil is supplied to the bore 29 and housing 28 through a 40 supply passage 77 formed in the side of the housing 28 and closed by a screw 78. The spindle 13 and its bearing 30 are partly lubricated by oil supplied thereto through a wick 79 which is positioned in an axially extending bore 80 formed in 45 the spindle 13. Transverse holes 81 are formed in the spindle 13 communicating with the bore 80 therein through which oil flows from the wick 79 to the contacting surfaces of the bearing 30 and spindle 13. Since a body of oil is always 50 maintained in the bottom of the housing 28, the lower end of the wick 79 is always immersed in oil. The contacting surfaces of the spindle 13 and bearing 30 are also supplied with oil which 55 passes thereto through a passage 82 formed in the bearing 30 and communicating with the interior of the housing 28 above the gear 33. The rotation of the gear 33 in the body of oil maintained within the housing 28 causes a portion of the oil to be thrown upwardly by centrifugal 60 force, into the passage 82 through which it passes to the contacting surfaces of the spindle 13 and bearing 30.

While we have shown a particular embodiment 65 of our invention, we do not desire our invention to be limited to the particular construction shown and described and we intend in the appended claims to cover all modifications within the spirit and scope of our invention.

What we claim as new and desire to secure by 70 Letters Patent of the United States is:

1. In combination, a magneto provided with a rotatable shaft and a rotor mounted on said shaft, an actuating spindle for an internal combustion engine distributor, said shaft having an 75

extended splined portion, a helical gear slidably mounted on said splined portion of said shaft, biasing means for biasing said helical gear against axial movement along said splined portion of said shaft, a second helical gear secured 5 to said spindle and meshing with said first named helical gear, and manually operable means for selectively displacing said first named helical gear axially along said splined portion of said shaft against the biasing force exerted thereon 10 by said biasing means to vary the angular relation between said spindle and said shaft about their respective axes, said manually operable means including an axially slideable cam associated with said first named helical gear and a 15 manually movable cam contacting with said first named cam.

2. In combination, a magneto provided with a frame and a rotor having a rotatable shaft journaled in said frame, said shaft being provided 20 with a splined portion extending outside said frame, a housing projecting from said frame and surrounding said splined portion of said shaft, an actuating spindle for an internal combustion engine distributor, one end of said spindle extending into said housing, a helical gear slidably mounted on said splined portion of said shaft within said housing, a second helical gear secured to said portion of said spindle within 25 said housing and meshing with said first named helical gear, and manually operable means including an operating member mounted on the outer end of said housing for selectively displacing said first named helical gear axially along said 30 splined portion of said shaft to vary the angular relation between said spindle and said shaft about their respective axes.

3. In combination, a magneto provided with a frame and a rotor having a rotatable shaft journaled in said frame, said shaft being provided with a portion extending axially beyond said frame, a housing projecting from said frame and surrounding said extended portion of said shaft, a combustion engine distributor housing mounted 45 on said first named housing, an actuating spindle for the combustion engine distributor extending into said distributor housing and into said first named housing, means including meshing gears secured to said shaft and to said spindle 50 respectively for connecting said spindle and said shaft in driving relation, and manually operable means including an operating member mounted on the outer end of said first named housing for selectively moving one of said gears with respect 55 to the member to which it is secured to vary the angular relation between said spindle and said shaft about their respective axes.

4. In combination, a magneto provided with a frame and a rotor having a rotatable shaft journaled in said frame, said shaft being provided with a splined portion extending outside said frame, a housing projecting from said frame and surrounding said splined portion of said shaft, an actuating spindle for an internal combustion engine distributor, one end of said spindle extending into said housing, a helical gear slidably mounted on said splined portion of said shaft within said housing, means including a 60 compression spring for biasing said helical gear against axial movement along said splined portion of said shaft, a second helical gear secured to said portion of said spindle within said housing and meshing with said first named helical gear, 65

said housing having a bore formed therein substantially in alignment with said shaft, and manually operable means for selectively displacing said first named helical gear axially along said 5 splined portion of said shaft to vary the angular relation between said spindle and said shaft about their respective axes, said last named means including a manually movable cam slidably mounted in said bore in said housing and a second 10 cam associated with said first named helical gear and contacting with said first named cam.

5. In combination, a magneto provided with a frame and a rotor having a rotatable shaft journaled in said frame, said shaft being provided 15 with a splined portion extending outside said frame, a housing projecting from said frame and surrounding said splined portion of said shaft, an actuating spindle for an internal combustion engine distributor, one end of said spindle extending into said housing, a helical gear slidably mounted on said splined portion of said shaft within said housing, means including a compression spring for biasing said helical gear against 20 axial movement along said splined portion of said shaft, a second helical gear secured to said portion of said spindle within said housing and meshing with said first named helical gear, said housing having a bore formed therein substantially in alignment with said shaft and said helical 25 gear having an axial projection formed thereon adjacent said bore, an axially movable cam member slidably mounted in said bore, means including an anti-friction thrust bearing for connecting said helical gear and said cam member, said 30 thrust bearing being provided with a race mounted on said projection on said first named helical gear and a race secured to said cam member, and manually operable means including an operating member mounted on the outer end of said housing 35 and a second cam member rotatably mounted in said bore and contacting with said first named cam member for selectively displacing said first named helical gear axially along said splined portion of said shaft against the biasing force 40 of said biasing means to vary the angular 45 relation between said spindle and said shaft about their respective axes.

6. In combination, a magneto provided with a frame and a rotor having a rotatable shaft journaled in said frame, said shaft being provided 5 with a portion extending outwardly beyond said frame, a housing projecting from said frame and surrounding said extended portion of said shaft, an actuating spindle for an internal combustion engine distributor having one end thereof extending 10 into said housing, means including a bearing secured to said housing for supporting said spindle, means including meshing gears secured to said shaft and said spindle respectively for connecting said spindle and said shaft in driving relation, said housing having a reservoir formed in the lower portion thereof adapted to contain lubricant for said gears, said spindle having an axially extending bore formed therein, and means including a wick mounted in said bore formed in 15 said spindle and extending into the lubricant contained in said reservoir for supplying lubricant to said spindle bearing.

7. In combination, a magneto provided with a frame and a rotor having a rotatable shaft journaled in said frame, said shaft being provided with a portion extending outwardly beyond said frame, a housing projecting from said frame and surrounding said extended portion of said shaft, an actuating spindle for an internal combustion 30 engine distributor having one end thereof extending into said housing, means including a bearing secured to said housing for supporting said spindle, means including meshing gears secured to said shaft and said spindle respectively 35 for connecting said spindle and said shaft in driving relation, said housing having a reservoir formed in the lower portion thereof adapted to contain lubricant for said gears, and means for conveying lubricant thrown from the surface of 40 at least one of said gears by centrifugal force during the rotation thereof to said spindle bearing.
